SEWING MACHINE

Louis Kaufman, Brooklyn, N. Y.

Application March 9, 1938, Serial No. 194,760

3 Claims. (Cl. 112—144)

This invention relates to a method and machine for making the embroidery shown herein.

One object of the present invention is to provide a novel and improved method and means for making an embroidered product comprising a fabric having a row of separated and disconnected stitches showing on the face thereof.

Another object is to provide a novel and improved method and means for making a chain stitch in such a way that only separated and disconnected stitches are visible on the face of the material.

Various other objects and advantages will be apparent as the nature of the invention is more fully disclosed.

Although the novel features which are believed to be characteristic of this invention are particularly pointed out in the claims appended hereto, the invention itself will be better understood by referring to the following description, taken in connection with the accompanying drawings, in which a preferred embodiment thereof has been set forth for purposes of illustration.

In the drawings:

Fig. 1 is a top plan view of a machine embodying the present invention showing the embroidered product being made thereon;

Fig. 2 is a side elevation of the machine shown in Fig. 1;

Fig. 3 is an enlarged end elevation of the machine showing the needles and cooperating mechanism;

Fig. 4 is a detail of the feed plate showing a portion of the blade for folding and guiding the fabric;

Fig. 5 is a detail showing the arrangement of the feed dogs and the associated mechanism;

Figs. 6, 7, 8, and 9 are details showing successive needle positions for forming the stitch.

In the following description, and in the claims certain specific terms are used for convenience in referring to various parts of the invention. These terms, however, are to be given as broad an interpretation as the state of the art will permit.

The present invention may be embodied in an attachment for or a modification of a standard, two needle, chain stitch sewing machine made for use on straw and the various parts of the mechanism which are incorporated in such machine are not described herein in detail.

The machine comprises in general a sewing machine head 15 carrying a presser foot bar 17 and a needle support 18 which are actuated by suitable mechanism, not shown, from a source of power such as a belt pulley 20. The machine is also provided with a set of pusher fingers 23 as shown in Figs. 5 to 9 which assist in forming the chain stitch in the manner to be described.

The needle support 18 carries a pair of needles

21 and 22 which are spaced apart by a distance corresponding to the length of the desired visible stitch. One of these needles, such as the needle 21, is provided with the usual eye 24 to receive the thread. The other needle 22 is provided with a hook 25 which engages the thread for pulling the same downwardly through the fabric. This machine is designed to work on stiff, heavy material such as straw and in its original form is not adapted to work on light weight, thin, flexible material such as fabric. Furthermore, it is intended to produce a narrow stitch which is practically invisible on the surface of the straw.

In accordance with the present invention, a feed plate 28 is provided having an aperture 29 through which a pair of feed dogs 30 extend. At its forward end the aperture 29 is divided into two parts by a bridge member 31 having an aperture 32 therein to receive the needles 21 and 22. The bridge member 31 may be extended between the two feed dogs 30 the entire length of the aperture 29 if desired. This bridge member serves as a support for the fabric and ensures the proper feeding thereof by the feed dogs. The plate 28 is provided at its front end with a downwardly curved flange 33 which receives and guides the fabric over the aperture 29. The rear end of the plate may be bent downwardly as at 34 to facilitate the proper discharge of the stitched fabric thereover.

A presser foot 38 is attached to the presser foot bar 17 by means of a screw 39. This presser foot 38 is provided on its forward edge with an outwardly curved flange 40 and with an aperture 41 to receive the needles. The position of the presser foot is controlled by a handle 42 in the usual manner. It is to be understood that the feed dogs 30 are actuated by standard mechanism for advancing the material step-by-step after each stitch.

In order to feed the fabric to the needles folded to produce the desired tucks or pleats, a blade 45 may be provided which extends to the front of the machine and is supported on an extensible arm 46 which is pivoted to a bracket 47. The blade 45 may be provided with a finger 48 which extends past the edge of the aperture 32 so as to properly hold the fabric while it is being stitched. The finger 48, however, terminates short of the path of travel of the feed dogs 30. The blade 45 may also be provided with a rounded recess 49 which provides clearance for handling the cloth. A stop 50 may also be attached to the bracket 47 to limit the movement of the blade 45 so that it cannot be brought into the path of the needles. The bracket 47 may be attached to the table or base by means of screws 51 extending through ears 52 formed thereon. In order to adjust the width of the tucks or pleats, the length of the arm 46 is made adjustable by means of screws 60

53 extending through elongated slots 54 formed therein.

In order to properly gauge the spacing of the tucks, a guide 60 is provided. This guide is attached to a rod 61 which extends horizontally at the front of the machine and is adjusted and secured by a set screw 62. The gauge 60 extends around the edge of the blade 45 and is provided with a downwardly directed flange 63 which is adapted to engage under the preceding tuck for guiding the goods over the blade 45.

The method of making the stitch is best shown in Figs. 5 to 9. It will be noted that a thread 65 is threaded through the eye 24 in the needle 21 and is pushed upwardly through the fabric 66 by said needle as shown in Fig. 6. The pusher fingers 23 then engage the thread and shift the same laterally so that it is engaged by the hook 25 of the needle 22 as shown in Figs. 7 and 8.

20 When the needles are retracted the thread is drawn downwardly by the hook 25 and forms a loop 67 below the fabric. The fabric is now advanced by the action of the feed dogs 30. As the fabric is advanced, this loop 67 is brought over the point of the needle 21. The next upward thrust of the needle 21 passes through this loop to secure the same and form a chain stitch.

It will be noted that the machine above described forms a continuous chain stitch as shown in Fig. 9 on the underside of the fabric. On the face of the fabric, however, a plurality of spaced loops 68 are formed which are entirely disconnected and have the appearance of embroidery. 35 It is to be understood that the thread 65 may be of a different color from the fabric 66 so as to produce a contrasting design and that both the thread and the spacing of the needles are so selected as to produce loops 68 which stand out 40 in appearance with respect to the face of the fabric.

In order to make the tucks and secure the same by the above mentioned type of chain stitch, the fabric is first folded over the blade 45 and is fed to the path of the needles to form a row of 45 stitches which secure the fabric in the form of a tuck 70. When the next tuck is to be formed, the fabric is again folded over the edge of the blade 45 in such a manner that the guide 60 extends under the previously formed tuck into 50 alignment with the row of stitches securing the same. As the fabric is now advanced to the needles, a second tuck is formed with the row of 55 stitches spaced as above and visible as a row of separate, disconnected stitches spaced from the edge of the preceding tuck.

In the embodiment shown the stitches are formed about medially between the edges of successive tucks, but it is to be understood that they 60 can be formed at any point depending on the way the fabric is folded and the spacing between tucks. As shown in Figs. 6 to 9, the machine produces a product comprising a row of overlapping tucks each having a row of spaced stitches visible on the face thereof and secured by a continuous chain stitch on the underside which is concealed within the tuck. The appearance is similar to that produced by hand embroidery and may be used as a trimming or for other purposes as will be readily apparent.

70 This device may be used with fabrics of various thicknesses to produce different effects desired and the tucks may be made with any desired spacing or may be omitted. The spacing between the visible stitches is determined by

the action of the feed dogs 30 and the amount by which the fabric is fed between successive needle thrusts. The width of the visible stitch is determined by the spacing between the needles. The width of the tuck beyond the row of stitches is determined by the adjustment of the blade 45 and the distance between tucks is determined by the guide 60. By properly selecting and adjusting these elements any desired effect can be obtained.

10 While a particular embodiment of the invention has been shown for purposes of illustration, it is to be understood that various changes and modifications may be made therein as will readily appear to a person skilled in the art. The 15 invention is only to be limited in accordance with the following claims when interpreted in view of the prior art.

What is claimed is:

1. A sewing machine for making a tucked fabric product in which the tucks are each secured by a single row of stitches each row comprising stitching extending continuously along the under face of the fabric and visible on the front face between successive tucks as a plurality of spaced 25 disconnected double strand loops, said machine having a work support, stitch forming mechanism having a pair of spaced needles including a hooked end and an eyed needle, means beneath the work support to carry and actuate the needles from 30 the under side of the fabric, a tucking guide blade in advance of the needles over which the fabric is folded, a presser foot to compact the fabric and hold the same against the penetrating thrust of the needles and actuating mechanism to advance 35 the fabric to the needles.

2. A sewing machine for making a tucked fabric product in which the tucks are each secured by a single row of stitches each row comprising stitching extending continuously along the under face of the fabric and visible on the front face between successive tucks as a plurality of spaced 40 disconnected double strand loops, said machine having a work support, stitch forming mechanism having a pair of spaced needles including a hooked end and an eyed needle, means beneath the work support to carry and actuate the needles from the under side of the fabric, a tucking guide blade in advance of the needles over which the fabric is folded and a guide cooperating with said 45 blade to space the tucks, a presser foot to compact the fabric and hold the same against the penetrating thrust of the needles and actuating mechanism to advance 50 the fabric to the needles.

3. A sewing machine for making a tucked fabric product in which the tucks are each secured by a single row of stitches each row comprising stitching extending continuously along the under face of the fabric and visible on the front face between successive tucks as a plurality of spaced 55 disconnected double strand loops, said machine having a work support, stitch forming mechanism having a pair of spaced needles including a hooked and an eyed needle, looping mechanism to cooperate therewith to form chain 60 stitching, means beneath the work support to carry and actuate the needles from the under side of the fabric, a tucking guide blade in advance of the needles over which the fabric is folded and a guide cooperating with said blade to space the 65 tucks, a presser foot to compact the fabric and hold the same against the penetrating thrust of the needles and actuating mechanism to advance 70 the fabric to the needles.

LOUIS KAUFMAN.
